UNITED STATES PATENT OFFICE.

THEODORE WESTEN AND RALPH J. MOREHOUSE, OF VISALIA, CALIFORNIA.

RECEPTACLE-FILLING APPARATUS.

Application filed April 28, 1921. Serial No. 465,133.

To all whom it may concern:

Be it known that we, THEODORE WESTEN and RALPH J. MOREHOUSE, citizens of the United States, residing at Visalia, State of California, have invented a new and useful Improvement in Receptacle-Filling Apparatus, of which the following is a specification.

This invention relates to apparatus for filling boxes or other receptacles, and the primary purpose of the invention is to provide novel means for accurately and successively filling each of a plurality of receptacles to a given weight or measure without interrupting the flow of the commodity in transferring the latter from one receptacle to another.

Another purpose of the invention is to provide novel means, preferably automatic in its operation, for diverting the flow of the commodity from a receptacle that has been filled to desired capacity to another empty receptacle.

Other objects of the invention, as well as the details of construction and operation will be more readily understood from the following description and accompanying drawings, in which:

Figure 1 is a view partly in section and partly in elevation of an apparatus constructed in accordance with our invention.

Fig. 2 is an end elevation of the construction shown in Fig. 1.

Fig. 3 is a diagrammatic view of the circuit including the electromagnetic deflector actuating means.

Figs. 4 to 6 inclusive are views of details.

Briefly stated, the invention comprises a main hopper into which the commodity with which the receptacles are to be filled is initially introduced. This hopper is provided with an outlet through which the commodity is discharged in a downwardly falling stream. Positioned in the path of this stream is an oscillating deflector operable to divert the stream from one to another of a plurality of scale hoppers located beneath the main hopper. Means, automatic or manual in its operation, is provided for actuating the deflector to divert the stream from a hopper that has been filled to a de-

sired capacity to an empty hopper. Concave walls located on opposite sides of the deflector provide a passage through which the stream passes from the main hopper on its way to the scale hoppers and said walls are adjustable to prevent clogging of the deflector. Each scale hopper is provided with means for discharging the contents thereof into a suitably positioned receptacle adapted to serve as the ultimate container for the commodity.

Referring more particularly to the drawings, 11 and 12 designate a pair of tables supported each by a plurality of legs 13 depending therefrom. Each table is utilized to support thereon the base member 14 of a scale hopper 15, the scale or dial structure being designated 16, and adapted to indicate the weight of material deposited in the hopper 15 as will be well understood, although not shown in detail. Each hopper 15 has the bottom portion thereof divided into two sections 17 hinged to the body of the hopper as indicated at 18. Each section 17 is connected by a link 19 to one end of a bar 20. A bolt 21 passing through the intermediate portion of the bar 20 is movable vertically in a slotted guide member 22 secured to one end of the hopper and is adapted to be maintained in the elevated position shown in Fig. 1 by means of a wing nut 23 threaded on the outer end of the bolt and adapted to clamp the guide member 22 between the head 24 of the bolt and the plate 20. Upon referring to Figs. 1 and 6, it will be readily understood that by loosening the wing nut 23 and moving the bolt 21 downwardly in the guide member 22, the sections 17 will be swung to open position, while closing movement of said sections may be effected by raising the bolt 21 upwardly in the guide member 22 and tightening the nut 23 to maintain the sections closed.

In the present instance, two hoppers 15 are employed and both are contained within the lower open end of a rectangular casing 25. This casing is adjustably supported for vertical movement with respect to the tables 11 and 12 and the hoppers 15 through the medium of adjusting bolts 26 threaded upwardly through the horizontal arms 27 of a pair of brackets 28 carried by the tables 11

and 12, the free ends of said bolts being suitably engaged with posts 29 secured to opposite sides of the casing. Within the upper end of casing 25 are located a pair of 5 oppositely disposed inclined walls 30 defining between them a hopper 31 having a bottom outlet 32 controlled by adjustable slides 33. Any suitable means (not shown) may be provided for maintaining the slides 10 33 in adjusted position.

Disposed below and extending longitudinally of the hopper outlet 32 is a pivot shaft 34, the opposite ends of which are extended outwardly through opposite walls of the 15 casing 25, one of said ends being equipped with a rigid cross head 35. This shaft carries within the casing 25 an oscillatable deflector plate 36 secured to the shaft intermediate of its width, as shown to advantage 20 in Fig. 1, and provided with end flanges 37 adapted to bear against opposite walls of the casing 25. Supported directly below the shaft 34 is a stop bar 38. The bar 38 is triangular in cross section presenting upwardly 25 converging side walls 39 adapted for engagement with the underneath side of the deflector plate 36 to limit oscillation of the latter in either direction.

Located on opposite sides of the deflector 30 plate 36 are a pair of adjustable concave wall plates 40. Each plate 40 is suitably carried by the inner ends of a pair of adjusting screws 41, the outer ends of said screws being provided with heads 42. The 35 walls 40 define between them a passage for the stream of commodity falling from the hopper 31 and are adjustable relative to the deflector 36 to prevent clogging of the latter. Located beneath the scale hoppers 15 is a 40 suitable receptacle support 43, upon which the receptacles to be filled are disposed. This support may be in the form of an endless conveyor as shown in the present instance, and may be operable either manually 45 or automatically to successively dispose pairs of empty receptacles 44 below the hoppers 15 to be filled.

When it is desired to increase the capacity 50 of the hoppers 15, additional sections 15^a are associated therewith, the casing 25 being adjusted vertically to compensate for the increased depth of the hoppers. The additional sections 15^a are held in place by the fingers 15^b depending therefrom and adapted 55 to embrace the hoppers 15.

In practice, assuming the parts to be in the position shown in Fig. 1, the commodity with which the receptacles 44 are to be filled is initially placed in the hopper 31. From 60 this hopper, the commodity or material is discharged through the opening 32 in a falling stream against the deflector 36 being directed toward the central portion of the deflector by adjustable guides 33, to prevent 65 inadvertent actuation of the deflector as

would occur if the stream from the hopper were deflected against the uppermost edge of the deflector instead of against the central portion thereof. From the deflector 36, the stream passes into the left hand hopper 15 70 filling this hopper to the desired capacity. When the hopper has been thus filled to the desired capacity, the deflector 36 is oscillated either manually or automatically, as will be later described, to divert the stream into the 75 right hand hopper 15. By manipulating the nut 23 to open the doors 17, the material contained in the left hand hopper 15 may be discharged into the receptacle 44 disposed therebeneath, the sections 17 being subsequently swung to closed position to provide for refilling of the hopper.

Preferably, I desire that the deflector 36 be automatic in its operation and to this end, I provide a pair of solenoids 45 secured to one end of the casing 14. Each solenoid has the core 46 thereof connected, as by means of a link 47 to one end of the cross head 35. Each solenoid 45 is in circuit with a battery 48 and with one of the scales 16 having 90 one terminal thereof connected, as indicated at 49 to the pointer 50 of the scale, and the remaining terminal thereof is connected as indicated at 51 to one terminal of the battery 48, the opposite terminal of said battery 95 being connected as indicated at 52 to a contact plug 53. The plug 53 is adapted to be removably and adjustably associated with the scale 16, so as to contact with the pointer 50 when the latter reaches any desired 100 unit of measurement. In Fig. 3, the plug is shown as arranged to contact with the pointer 50 when the latter has been moved to indicate twenty pounds. With this arrangement, it will be evident that the flow 105 of material into one of the scale hoppers will continue until the weight of the material in the hopper becomes such as to move the pointer 50 of the scale into contact with the plug 53, thus closing the circuit to the solenoid associated with the hopper and causing 110 said solenoid, through its connection with the cross head 35, to reverse the position of the deflector 36, thus diverting the stream of commodity into the remaining hopper. 115 When this has been done, the contents of the filled hopper may be discharged into the receptacle 44 positioned therebeneath by loosening the wing nut 23 and moving the bolt 21 downwardly in the slotted guide 120 member 22 to swing the bottom sections 17 of the hopper to open position.

In some instances, however, it may be preferred to operate the deflector 36 by foot or hand power, and for this reason, we do not 125 wish to limit ourselves to the exact operating mechanism set forth herein, but reserve the right to resort to such modifications and changes both in the operating mechanism and in the other parts of the invention, as 130

may be desired and do not constitute a departure from the spirit and scope of the appended claims.

What is claimed is:

5. 1. A receptacle filling apparatus comprising a pair of rigidly supported relatively adjustable walls, means for producing a flowing stream of the commodity with which said receptacles are to be filled and causing said stream to pass between said walls and a deflector located between said walls operable to successively deflect the stream into each of the receptacles to be filled.
15. 2. A receptacle filling apparatus comprising means for producing a flowing stream of the commodity with which the receptacles are to be filled, a deflector movable into the path of the stream to successively divert the same into each of a plurality of receptacles, means for actuating said deflector, and adjustable means for regulating the point of impact between the stream and the deflector to prevent inadvertent actuation of the latter.
25. 3. A receptacle filling apparatus comprising means for producing a flowing stream of the commodity with which the receptacles are to be filled, a plurality of measuring hoppers, a deflector in the path of the stream adapted to deflect the latter successively into each of said hoppers, said deflector having a predetermined definite location with respect to the open ends of said hoppers, an additional hopper section adapted to be associated with each hopper to increase the capacity thereof, and means for adjusting said deflector when the additional hopper sections are in use to maintain the original definite location between the deflector and the open ends of the hopper.
40. 4. A receptacle filling apparatus, comprising means for producing a falling stream of the commodity with which the receptacles are to be filled, rigid concave walls providing between them, a passage for the said stream, means for adjusting said walls to vary the size of the passage and a deflecting member movable in the passage to divert the stream from one receptacle to another.
45. 5. A receptacle filling apparatus, comprising means for producing a falling stream of the commodity with which the receptacles are to be filled, spaced walls, providing a passage between them for the said stream, a deflector movable in said passage to divert the said stream from one receptacle to another, means for actuating said deflector, and means for varying the size of the passage, including supporting members connected to the said walls and adjustable to move the latter relatively to one another.
55. 6. A receptacle filling apparatus, comprising means for producing a falling stream of the commodity with which the receptacles are to be filled, a deflector located in the path of the stream and operable to deflect the stream from one receptacle to another, means for oscillating said deflector, and a stop member presenting oppositely sloping sides alternately engageable with the deflector to limit movement of the latter in either direction.
7. A receptacle filling apparatus comprising means for producing a falling stream of the commodity with which the receptacles are to be filled a deflector for diverting the stream from one receptacle to another, and electro-magnetic means for actuating said deflector, including a pair of solenoids and a cross head carried by the deflector and connected at its ends to the cores of the solenoids.
15. 8. A receptacle filling apparatus, comprising means for producing a falling stream of the commodity with which the receptacles are to be filled, a shaft, a deflector carried by the shaft and operable to divert the stream from one receptacle to another, a pair of solenoids mounted on opposite sides of the shaft, a cross head fixed to the shaft and linked at its ends to the cores of the said solenoids and means for alternately energizing the solenoids to effect oscillation of the deflector.
25. 9. A receptacle filling apparatus, comprising a casing, a hopper in the upper portion thereof, a pair of spaced concaved walls mounted in the casing below the hopper, adjusting screws threaded through the casing and supporting said walls and a deflector mounted between the walls.
35. 10. A receptacle filling apparatus, comprising a casing, a hopper in the upper portion thereof, spaced concave walls mounted in the casing below the hopper, a shaft extending between said walls, a deflector secured to the shaft with the longitudinal edges of the deflector projecting upon opposite sides of the shaft and a stop presenting sloping surfaces also projecting upon opposite sides of the shaft for engagement with the projecting portions of the deflector to limit the movement of the latter in either direction, and means for actuating said shaft to oscillate the deflector.
45. 11. A receptacle filling apparatus, comprising a casing, a hopper mounted in the upper portion thereof, a pair of spaced walls mounted in the casing below the hopper, a deflector mounted between said walls, scale hoppers supported below said deflector, means for increasing the capacity of the said scale hoppers and means for adjusting the position of the said casing to compensate for the increased capacity of the hoppers.
55. 12. A receptacle filling apparatus comprising a hopper, a shaft mounted below the hopper and equipped with a deflector, a cross head fixed to the shaft, a pair of solenoids, each having the core thereof con-

5 nected to one end of the cross head, a pair
of scale hoppers, each having a weighing
mechanism associated therewith including a
pointer, and a graduated scale for indicat-
ing the weight of the hopper contents, con-
10 tact plugs engageable with said graduated
scales to contact with the pointers upon
movement of the latter to predetermined
units of measure on the scales and a nor-
mally open circuit including therein the
15 solenoids, plugs, and pointers and adapted to
be closed by engagement of the pointers
with the said plugs.

13. A receptacle filling apparatus, com-
15 prising a casing, a hopper mounted in the
upper portion thereof, spaced concaved

walls mounted in the casing below the hop-
per, a deflector mounted between said walls,
scale hoppers enclosed by the lower portion
of the casing, each of said hoppers having 20
weighing mechanism associated therewith,
including a pointer and a graduated scale
over which the pointer is movable to indi-
cate the weight of the hopper contents, and
electro-magnetic means for actuating the de-
flector to shut off the flow of each hopper
upon movement of the pointer thereof to a
predetermined unit on the associated gradu-
ated scale.

THEODORE WESTEN.
R. J. MOREHOUSE.
